UNITED STATES PATENT OFFICE.

WILLIAM H. DAMON, OF LOS ANGELES, CALIFORNIA.

DISPENSING VESSEL.

1,401,763.

Specification of Letters Patent. Patented Dec. 27, 1921.

Application filed December 11, 1919. Serial No. 344,180.

To all whom it may concern:

Be it known that I, WILLIAM H. DAMON, a citizen of the United States, residing at Los Angeles, in the county of Los Angeles and State of California, have invented new and useful Improvements in Dispensing Vessels, of which the following is a specification.

This invention relates to dispensing devices and more particularly to a measuring liquid dispensing can, and has for its object to provide a device whereby the quantity of liquid contained and being dispensed can readily be indicated and by which the discharge of the liquid can be readily controlled, and has further to provide a device of this character that is simple, inexpensive, and substantial.

The invention consists of the construction and details, an embodiment of which is illustrated in the accompanying drawings and described and claimed herein.

Figure 1 is a plan view of the improved measuring dispensing can.

Fig. 2 is a side elevation of the same.

Fig. 3 is a section on the line 3—3 of Fig. 2.

Fig. 4 is a vertical central section on the line 4—4 of Fig. 1, the handle being in elevation.

The improved device consists of a vessel or can of suitable proportions and material, in this case being cylindrical and having at its top a ring 3 provided with a gauze or other screen material 4, and at one side a handle 5. The lower end of the can 2 is provided with a bottom 6 that is elevated above the lower edge of the vessel or can body providing a space below the bottom part 6 in which there is an elbow 7 that is attached as by a flange 8, or otherwise, to the bottom 6 and coordinate to an outlet opening 9. This opening is covered by a sleeve closing valve 10 of the flap type having an upwardly extending arm 11 against which reacts an expansion spring 12, the opposite end of which is seated against a contiguous portion of the can body, as shown in Fig. 4.

By thus providing the elevated bottom 6, it is possible to utilize a flexible dispensing tube or spout 13 that can be slipped onto the horizontal arm of the outlet elbow 7 and in a position of non-use the spout 13 is turned upwardly along the side of the can 2 and may be retained temporarily by a hook or

clip 14 provided adjacent the upper end of the can.

From this it will be seen that the can can be set on its lower base or lower edge without interference of the spout which will pass through an opening 2' provided therefore in the front of the lower end of the can, and by retaining the spout in the upright position this will overcome the dripping of any oil or other material that may have been just previously dispensed from the device.

To facilitate the control of the discharge of the contents from the vessel or can it is preferable that means be located exterior of the can and also within convenient reach of the thumb or one of the fingers of a hand gripping the handle 5, and this is accomplished by pivoting a thumb lever 15 at the upper end of the can in a position contiguous to the upper end of the handle 5, this lever having an arm 16 extending into the can 2 and having a link 17, the lower end of which is pivoted at 18 to the flap valve 10, so that by depressing the thumb lever 15 the valve can be opened at will to a desired degree.

A further feature of the invention provides for observation of the quantity of the material, as oil, in the can 2, or that is dispensed from the can, and measuring or indicating means consisting of a transparent, longitudinally extending window or gauge 20 mounted in a slot 21 provided therefor, and the measurement of the quantity visible through the window may be secured by relative graduation marks 22, in this case formed on the face of the window 20, although it is obvious that these marks may be otherwise located.

From the above it will be seen that when it is desired to dispense a given quantity of substance from the can the latter can be filled with a measured quantity, or having been charged, a measured quantity can be run off by disconnecting the flexible spout 13 from its retainer 14 and lowering the spout to a point below the discharge valve, generally, and then by pressing the thumb lever the quantity of oil desired can be dispensed from the can.

Various changes may be made without departing from the spirit of my invention as claimed.

I claim:

In a measuring and dispensing vessel, a

container having a bottom that is elevated with respect to the lower edge of its wall, said elevated bottom being provided with a discharge opening, an L-shaped tubular connection secured to the underside of the bottom and communicating with the opening therein, a flexible tube having one end secured to said L-shaped connection, a substantially L-shaped valve hinged to the top 5 of the bottom, the horizontal member of which L-shaped valve is adapted to normally close the discharge opening in the

bottom, a compression spring interposed between the wall of the container and the upright member of the L-shaped valve, which 15 spring normally exerts pressure to maintain the valve in closed position, a thumb lever fulcrumed on the upper portion of the container, and a connection from the inner end of said thumb lever to the horizontally disposed portion of said L-shaped valve. 20

In testimony whereof I have signed my name to this specification.

WILLIAM H. DAMON.
